UNITED STATES PATENT OFFICE.

RUFUS A. CROW, OF KIRKSVILLE, MISSOURI.

RAILWAY-TIE.

1,097,394.

Specification of Letters Patent. Patented May 19, 1914.

Application filed March 22, 1913. Serial No. 756,209.

To all whom it may concern:

Be it known that I, RUFUS A. CROW, a citizen of the United States, residing at Kirksville, in the county of Adair and State 5 of Missouri, have invented new and useful Improvements in Railway-Ties, of which the following is a specification.

The present invention relates to improvements in ties for railway rails and means 10 for securing the rails upon the ties, and the improvement resides in the construction, combination and operative arrangement of parts set forth in the following description and falling within the scope of the appended 15 claim.

In the drawing: Figure 1 is an end view of a tie constructed in accordance with my improvement showing the rails secured thereto, Fig. 2 is a central longitudinal sec- 20 tional view of the same, Fig. 3 is a top plan view of the same, and Fig. 4 is a perspective view of one of the rail securing clamps.

The tie comprises a rectangular member 25 which has integrally formed upon its upper face a longitudinally extending rib or enlargement 5 which, adjacent its opposite ends, is cut flush with the tie to permit of rails R resting directly upon the tie. One 30 of the transverse walls provided by each of the cut-away portions of the rib or enlargement 5 has its underface beveled to provide a lip 2 which engages with the base flange of the rails. The opposite walls provided 35 by the said cut portions of the rib are formed with V-shaped depressions 12. The tie between the lips 2 and the depressed walls 12 is formed with openings 4, the side walls of which being vertically straight and par- 40 allel, and the end walls being inclined. One of the inclined end walls is adapted to communicate with the upper face of the tie at a point away from the inner wall of the lip 2 equaling the width of the base flange of the rails R, while the second transverse wall of each of the said openings communicates with the face of the tie a suitable distance away from the depressed walls 12 of the rib 5.

50 The clamps each comprise a head 7 and a body 10. The head at one of its ends is formed with a lip 8, the under face of which

being beveled to agree with the upper face of the base flange of the rail with which it is adapted to engage. The opposite end of the 55 head is formed with a V-shaped depression 9 which is adapted to be arranged adjacent one of the V-shaped walls in the rib 5. The sides of the clamp are arranged in a line with the heads 7 thereof, but the trans- 60 verse walls or ends are inclined, as at 11, to agree with the inclined transverse walls of the openings 4. When the clamps have their bodies inserted within the openings 4, the transverse walls 11 engage with the angular transverse walls provided by the open- 65 ings 4, and the lip 8, as stated, overlies the base flange of the rail, while a securing element in the nature of a rectangular bolt is passed through the depressions 9 and 12 70 in the clamp and rib. The bolt is provided with a threaded end 14 which receives a nut 13.

The underface of the tie adjacent its ends and away from its openings 4 is formed 75 with transverse ribs 3 to insure the same against movement when tamped within the roadbed.

It is to be noted that by the co-engagement of the angular walls or ends of the 80 bodies of the clamp the transverse walls of the openings of the tie are so arranged as to prevent the upward movement of the clamp and also that one of the walls of each of the clamps underlies each of the rails. 85 It will be further noted that the headed portions of the clamps are of a size equaling the depth of the rib and the body is of a length equaling the thickness of the tie.

What I claim is:

90 A tie having its upper face formed with a centrally arranged longitudinally extending enlargement which is cut away to permit of rails resting directly upon the upper face of the tie, one of the end walls provided 95 by the cut away portion of the enlargement having its underface inclined to provide a rail base engaging lip, the opposite wall being V-shaped, the tie between the lip and the said V-shaped wall having an opening, 100 the end walls of which are angular, clamps, each of the clamps including a body and a head, the head having one of its ends formed with a lip which is adapted to engage with

the base flange of the rail opposite that engaged by the lip, the opposite end of each head having a V-shaped depression, the body having its ends angular to coincide with 5 the angular walls of the opening in the tie within which it is adapted to be received, bolts passing through the V-shaped walls of the enlargement of the tie and the V-shaped

recesses in the heads of the clamps, and securing members for the bolts. 10

In testimony whereof I affix my signature in presence of two witnesses.

RUFUS A. CROW.
